INVENTOR
BY PETER M. ERDMAN
A. B. Bowman
ATTORNEY

UNITED STATES PATENT OFFICE

PETER M. ERDMAN, OF LOS ANGELES, CALIFORNIA

OIL TANK CLEANING DEVICE

Application filed March 17, 1930. Serial No. 436,477.

My invention relates to a device for cleaning storage tanks, and more particularly oil storage tanks.

The objects of my invention are: first, to provide a cleaning device for oil tanks whereby the sediment or other foreign matter may be removed from the bottom of the tank without the necessity of emptying the same; second, to provide a tank cleaning device whereby the entire area of the tank bottom is cleaned at one time; third, to provide a tank cleaning device which may be used whenever desired for cleaning the tank, and without regard to the quantity of fluid contained in the tank; fourth, to provide a tank cleaning device which may be readily installed, one which is simple and economical of construction, durable, and will not readily deteriorate or get out of order.

With these and other objects in view, as will appear hereinafter, my invention consists of certain novel features of construction, combination and arrangement of parts and portions, as will be hereinafter described in detail and particularly set forth in the appended claims, reference being had to the accompanying drawings and to the characters of reference thereon which forms a part of my application, in which:

Figure 1 is a plan view of my device, in one form, positioned in a tank for use; Fig. 2 is a side elevation of my device as shown in Fig. 1, showing the tank in section; and, Fig. 3 is a plan view of a modified form of my device.

Like characters of reference refer to similar parts and portions throughout the views of the drawings.

My tank cleaning device consists in one form, as shown in Figs. 1 and 2, of several pipes 1, provided with multiplicities of openings, supports 2 for supporting the pipes, a union 3, a reducer 4, and elbow means connecting the device through the tank 5 to a suction pipe 6.

The pipes 1 are supported above and on the bottom of the tank 5 by means of the supports 2. These pipes are so arranged that they form substantially a network over

of sediment or other foreign matter. In Figs. 1 and 2, there are shown two pipes 1 which are joined at their discharge ends to a short pipe section 7 which forms with the pipes 1 a Y. The pipes 1 are provided with a number of openings 1a, 1b and 1c at the outer end and intermediate the ends of the pipes, said openings being in the form of downwardly directed pipe sections from the pipes 1 and spaced with their lower ends from the bottom of the tank. In this instance, assuming the pipes 1 to be three inches in diameter, the openings 1a at and near the outer ends of the pipes 1 are preferably three inches in diameter; the openings 1b intermediate the ends of the pipes 1 are two inches in diameter; and the openings 1c at the inner ends of the pipes 1, or other convenient place, are one inch in diameter. It will be noted that the larger openings, as shown, are further from the outlet or suction pipe 6 than are the smaller openings, thus creating substantially equal suction at all the inlet openings, making it possible to draw the sediment or other foreign matter through all of the openings, thereby cleaning the entire bottom of the tank. The pipe section 7 is connected by the union 3 to the reducer 4 which is connected to an elbow 8 directed with its other end through the bottom of the tank and connected to an elbow 9 which is connected to the suction pipe 6. The inner or discharge ends of the pipes are thus supported from the bottom of the tank by the elbow 8, while the extended ends are supported by the supports 2. Similar supports 2 may be provided intermediate these points of support. The supports 2 may consist of cross members provided at the ends provided with downwardly extending legs resting on the bottom of the tank, thus providing a support offering as little resistance to the inlet openings for the sediment or other foreign matter as possible. The cross members of the supports are secured in any suitable manner to the pipes.

The suction pipe 6 is connected to a suitable pump, not shown, the discharge from the tank being controlled by a valve 10.

- In oil storage tanks, the sediment in the oil, as well as water and other foreign matters, settles to the bottom. It has been customary heretofore to remove such sediment and other foreign matter by first removing the oil from the top of the tank and leaving such sediment and other foreign matter, and then afterwards removing the latter, necessitating always the emptying of the tank.
- With my device the sediment and other foreign matter is removed from the bottom of the tank while the oil is retained therein, and without materially disturbing the contents therein.
- In the modified form of my device, as shown in Fig. 3, I have shown a main or central pipe 11 from which extend angularly to the opposite sides pipe sections 12 and 13. The end of the pipe 11 and the ends of the pipe sections 12 and 13 are provided with supports 2 for supporting the same from the bottom of the tank. At the end of the pipe 11 and the ends of the pipe sections 12 are openings of equal diameter. At the ends of the pipe sections 13 and at the intersections of the sections 12 with the pipe 11 are other openings of smaller diameter; and at the intersection of the pipe sections 13 with the pipe 11 is an opening of still smaller diameter. With this modified form of construction, there is provided a device in which the suction openings are more uniformly distributed over the bottom of the tank.
- Though I have shown and described a particular construction, combination and arrangement of parts and portions, and a certain modification thereof, I do not wish to be limited to this particular construction, combination and arrangement, nor to the modification, but desire to include in the scope of my invention the construction, combination and arrangement substantially as set forth in the appended claims.
- Having thus described my invention, what I claim as new and desire to secure by Letters Patent is:
1. In a structure of the class described, the combination of a tank, a plurality of pipes positioned slightly above the bottom of said tank, and means for supporting said pipes in said position, said pipes being provided with a multiplicity of openings along their lower side, said openings being smaller near the outlet than at the extremities of said pipes.
  2. In a tank cleaning device, the combination with a tank, of a plurality of pipes connected to a common outlet, said pipes having a multiplicity of openings along their lower sides, said openings being smaller near the outlet than at the extremities of said pipes.
  3. In a tank cleaning device, the combination with a tank, of a plurality of pipes connected to a common outlet, said pipes
- being supported a slight distance from the bottom of said tank and having openings, of various sizes, positioned along their lower sides at various distances from the outlet in a manner that the entire area of the tank bottom will be subject to suction from the pipes and be cleaned, the openings near the outlet being smaller than those farthest from the outlet.
4. In a tank cleaning device, the combination with a tank, of a plurality of pipes connected to a common outlet, said pipes being supported a slight distance from the bottom of said tank and having openings, of various sizes, positioned along their lower sides in a manner that the entire area of the bottom of the tank will be subject to suction from the pipes and be cleaned, said openings being larger at the extremities of the pipes than at the outlet ends thereof.
5. In a tank cleaning device, the combination with a tank, of a plurality of conductors connected to a common outlet, said conductors having a multiplicity of openings along their lower sides, the openings near the outlet being smaller than those farthest from the outlet.
- In testimony whereof, I have hereunto set my hand at Los Angeles, California, this 6th day of March, 1930.
- PETER M. ERDMAN.
